OF CINCINNATI, OHIO, A CORPORATION OF OHIO.

BUILDING-BLOCK TRUCK.

1,286,216.

Specification of Letters Patent.

Patented Dec. 3, 1918.

Application filed November 13, 1916. Serial No. 130,971.

To all whom it may concern:

Be it known that I, CLAUS O. BRANDELL, a citizen of the United States, and residing at Cincinnati, in the county of Hamilton and 5 State of Ohio, have invented a new and Improved Building-Block Truck, of which the following is a specification.

This invention relates to means for accelerating and insuring uniform curing or hardening concrete building blocks, and its object is to provide a device wherein the blocks can be cured in the least possible time and at a minimum cost.

This invention consists in a truck upon 15 which the building blocks may be stacked, a housing for the blocks mounted on the truck, means to secure a vapor-tight joint between the housing and truck, and means for supplying steam to the inside of the housing.

20 In the accompanying drawings Figure 1 is a side elevation of this improved truck with the housing in position, one corner of the housing being broken away to show the interior thereof. Fig. 2 is a vertical transverse section of the truck. Fig. 3 is an end elevation of the truck. Fig. 4 is a detail showing the method of constructing the housing. Fig. 5 is a detail showing the method of sealing the joint between the 25 housing and the body of the truck.

Similar reference characters refer to like parts throughout the several views.

It has been found that concrete building blocks can be cured in very much less time 35 within a room filled with steam than when the blocks are stacked up outside in the open air and sprinkled regularly with water. The objection to curing the blocks within a steam chamber is that the large spaces usually required for the handling of the blocks cause a loss of steam, and furthermore it has been found that the blocks do not cure evenly in such steam chambers and that therefore a longer time is required to cure all the blocks 45 than is necessary to finish individual ones. It is practically impossible to fully saturate the air in a large curing chamber as completely as in a small casing or housing. It has also been found that the repeated handlings of the blocks in passing from the block machine to the steam chamber are liable to cause hair cracks in the block, which materially impairs the crushing strength thereof. In the construction shown in the 50 drawings a truck of ordinary construction

is shown provided with a cover and means to supply steam to the interior of the cover. Blocks can be placed in racks on the truck if desired and need not be moved until fully cured. It will be understood that a sufficient 60 number of properly equipped trucks must be provided to take care of the output of the plant.

The construction of the truck itself may be of any well known construction, consisting of a bed 3, pedestals 4, axles 5 and wheels 6 running on the rails 7. If it is desired to lock the truck to the rails at any particular point, a hook 8 may be formed to engage a plate 9 at the lower end of one of the pedestals. A scaffolding 10 of any desired construction may be mounted on the truck to support the concrete blocks 12 resting on their pallets 13. These pallets will of course be those against which or on which the block 75 is formed in the machine. Any desired type of framework may be employed.

The construction of the cover or housing may be varied as desired. That shown consists of plates 15 of sheet metal bent to form 80 the roof 16 and the sides 17 of the housing. The several plates 15 are flared out at their adjacent edges to constitute flanges 18 that are secured together by the rivets 19, as shown in Fig. 4. The ends 20 are preferably bent to lap over the outer edges of the end plates 15 to constitute flanges 21 which may be secured to the outer plates 15 by means of rivets 23.

The lower edges of the ends and sides of 90 the housing extend down into a trough 24, as shown in Figs. 2 and 5, and this trough may be filled with any proper liquid 25, such as water or oil, to form a seal between the truck bed 3 and the housing and prevent 95 the escape of steam from the curing chamber. For the purpose of raising and lowering the housing, T bars 26 having holes 27 at their upper ends may be secured to the ends of the housing and into these holes the 100 hooks 28 on cables 29 may engage. The weight of the housing may be provided for by means of the counterbalance 30 attached to these cables 29 which extend around the pulley 32.

A steam main 34 will extend adjacent the tracks 7 and have valves 35 connected to it. Nipples 36 extend down from these valves and a flexible connection in the form of a rubber hose 37 may be secured to this nipple 110

2

by means of a clamp 38. The lower end of the rubber tubing may be secured to the elbow 39 by means of another hose clamp 40. The elbow 39 connects to a fitting 42, preferably in the form of a T, and this fitting may connect to the cross pipe 43 and the vertical pipe 44. The cross pipe 43 connects to an elbow 45 and that in turn to a vertical pipe 46. The lower ends of these pipes 44 and 46 connect 10 into T's 47 which receive the longitudinal pipes 48, formed with any desired number of discharge openings so that steam from the main 34 may flow along the bottom of the housing and discharge directly toward 15 the blocks carried by the truck. These pipes are preferably located at or near the lowest portions of any of the blocks within the housing in order that the entire mass of all the blocks may be affected by the steam. 20 These pipes 48 may be omitted should it be found that because of the size and proportions of the truck and the housing thereon it is necessary to discharge the steam only at the middle of the truck.

25 After the rack on the truck has been filled, the truck will be pushed on the track until it is below the desired housing, whereupon the hook 8 may be used to secure the truck in position. The housing is then lowered 30 down onto the truck and the flexible connection 37 employed to join the nipple 36 to the elbow 37. A long flexible connection will obviate the necessity of making connections. Steam is then admitted by opening the valve 35. After a period of from eight 35 to twelve hours the blocks will be found ready to be removed from the curing chamber.

ber. The time of turning on the steam may be indicated by one hand 50 of an indicator 51, whereupon the time for turning off 40 the steam will be indicated by means of the hand 52. These two hands will be adjustable relative to each other but will normally be moved together.

This invention does not include the construction of the framework or racks, nor does it include the details of construction of the housing. The details and proportions of these parts may all be changed by those skilled in the art without departing from 45 the spirit of my invention.

I claim:

1. In a device for curing concrete building blocks, the combination of a truck having a bed provided with a circumferential groove, a housing for the truck having its lower edge extending into this circumferential groove, perforated pipes secured to its walls to conduct steam to the interior of the housing, and means to prevent the escape of 55 the steam between the lower edge of the housing and said truck.

2. A device for curing concrete blocks consisting of a truck, means thereon to support the blocks to be cured, a housing adapted to be lowered down onto the truck and incase the blocks, and means carried by the housing for conveying steam to the interior of the cover and consisting in perforated pipes extending longitudinally of the truck 60 near the lower edges of the sides of the housing.

CLAUS O. BRANDELL.
